UNITED STATES PATENT OFFICE.

CHESTER HANES AND ROBERT H. MONTEITH, OF NEW RICHMOND, OHIO.

ELLIPSOGRAPH.

No. 830,784.

Specification of Letters Patent.

Patented Sept. 11, 1906.

Application filed November 6, 1905. Serial No. 286,054.

To all whom it may concern:

Be it known that we, CHESTER HANES and ROBERT H. MONTEITH, citizens of the United States, residing at New Richmond, in 5 the county of Clermont, State of Ohio, have invented certain new and useful Improvements in Ellipsographs; and we do hereby declare the following to be a full, clear, and exact description of the invention, such as 10 will enable others skilled in the art to which it appertains to make and use the same.

This invention relates to drafting instruments, and more particularly to ellipsographs, and has for its object to provide an 15 instrument of this kind which will be adjustable to describe ellipses of different dimensions, which may also be adjusted to describe circles of varying sizes, and which may be folded to occupy little space when not in 20 use.

Other objects and advantages will be apparent from the following description.

In the drawings forming a portion of this specification, and in which like characters of 25 reference indicate similar parts in the several views, Figure 1 is a top plan view of the present instrument adjusted to describe an ellipse. Fig. 2 is a front elevation. Fig. 3 is a view, partly in section and partly in elevation. Fig. 4 is a detail view of the notched leg. Fig. 5 is a sectional view through the main clamping mechanism.

Referring now to the drawings, the present invention comprises a foldable frame including upper and lower horizontally-disposed vertically-spaced guide-plates 5 and 6, respectively, which are disposed normally in crossed relation at right angles to each other and which have longitudinally-extending 35 slots 5' and 6', respectively.

The ends of the plates 5 and 6 lie in alignment with each other transversely of the frame and are connected at one end of the frame by a brace-bar 7, having its ends 45 turned to lie in vertically-spaced planes and against the under and upper faces of the plates 5 and 6, respectively, the brace-bar being pivoted to the ends of these plates and having fingers 7' thereon for engagement of 50 fingers 8 and 9, carried by the plates 5 and 6, respectively, to limit the movement of these plates away from the brace-bar, these fingers lying in mutual engagement when the frame is in operative position. The opposite ends 55 of the plates 5 and 6 are connected by an extensible brace-bar 10, including two slidably

connected members 11 and 12, this brace-bar being thus longitudinally extensible and being pivoted to the ends of the plates at its ends.

Means (indicated at 13) is provided to hold the members 11 and 12 against movement with respect to each other. Supporting-legs 14 are provided and are located at the points of union of the plates and brace-bar, 60 these legs having upward extensions 15, which form pivot-pins for the plates, the brace-bars being rigidly mounted upon the legs. The leg 14, which lies at the point of union of the brace-bars 7 and plate 5, has 65 an inwardly-opening notch 16 therein for a purpose to be presently described, and, as shown in the drawings, the brace-bars have inwardly-extending end portions 7" and 11", respectively, the pivot-pins extending upwardly through these portions inwardly of 70 the intermediate portion of the brace-bar.

A slide 17 is engaged in the slot 5' for movement longitudinally thereof and has an upwardly-extending milled finger-piece 18, 80 and the slide is also arranged for rotation with respect to the plate 5. A horizontally-extending sleeve 19 is carried by the slide 17 below the plate 5, and a vertically-threaded passage 20 opens through the upper end of 85 the finger-piece 18 and communicates with the interior of the sleeve 19, a set-screw 21 being adjustably engaged in this passage.

An arm 22 is slidably engaged in the sleeve 19, the screw 21 being arranged for operation 90 to hold this arm at different points of its movement, and the arm has its forward end portion turned downwardly and rearwardly to lie in a horizontal plane and upon the upper surface of the plate 6, the major portion 95 of the arm lying between these two plates.

The rearwardly-turned portion of the arm 22 (indicated at 22') has a vertical perforation therethrough which receives a pin 23, carried by a plate 24, located beneath the 100 plate 6 and extending laterally beyond the slot 6' thereof, as does also the rearwardly-turned portion 22' of the arm 22, this rearwardly-turned portion being somewhat broadened. The pin 23 extends upwardly 105 through the slot 6' and is slidable and revolvable therewithin.

A laterally-extending finger 25 is carried by the plate 24 and extends therebelow, and formed through this finger there is a passage 110 26, which extends radially of the plate for the reception of an arm 27, having a downwardly-

directed lead-grip 28 at its forward end. A set-screw 29 is engaged in the finger 25 and is operable to impinge against the arm 27 to hold the latter at different points of its movement within the passage 26. The portion 22' of the arm 22 and the plate 24, together with the pin 23, form a slide A, movable longitudinally of the plate 6, and the pin 23 has a retaining-nut 23' located upon the upper end thereof.

In use when it is desired to describe an ellipse the arms 22 and 27 are adjusted to bring the slides to points between their ends and the finger-piece 18 is grasped and moved 15 longitudinally of the slot 5'. The finger-piece being at the same time rotated to cause the slide A to move longitudinally of the slot 6', as will be readily apparent, the forward end of the arm 27 will be moved to describe an ellipse. When it is desired to describe a circle, the slide 17 is moved to lie above and concentric with the pin 23, when rotation of this 20 slide will cause the lead-grip to describe a circle, the radius of which may be varied by shifting the arm 27 in the passage 26.

When it is desired to fold the present implement, the fastening means 13 is loosened and the brace-bar 10 is extended, the plates 5 and 6 being moved pivotally in opposite directions and toward the brace-bar 7. When in folded position, the plate 6 lies in the notch 16, formed in one of the legs 14, as described above. The fastening means 13 may be tightened to hold the instrument in folded 35 position.

What is claimed is—

1. In an instrument of the class described, the combination with vertically - spaced guides, of a slide rotatably mounted in the 40 upper guide for movement longitudinally of the guide, an upwardly-extending finger-piece carried by the slide, a horizontal sleeve carried by the slide below the guide, a plate slidably engaged in the sleeve, a set-screw 45 engaged in the slide for operation to impinge against the plate, said plate having a downwardly and rearwardly turned end lying above the lower guide, a plate disposed beneath the lower guide, an upwardly-extending pin carried by the second plate and extending through the lower guide and rigidly engaged in the rearwardly-turned end of the first-named plate, said plates being arranged for rotation and for longitudinal sliding movement with respect to the guide, a horizontal sleeve carried by the second plate, a horizontal arm slidably engaged in the second sleeve, a set-screw engaged in the second sleeve for operation to impinge against the arm, and a 55 marker carried by the arm.

2. An instrument of the class described

comprising a foldable frame including upper and lower spaced guides, slides removably mounted in the guides, a marker connected with one of the slides, a brace-bar pivotally connected with the end of each guide, an extensible brace-bar pivotally connected at its ends with the other ends of the guides, said brace-bars and guides having mutually-engaging fingers disposed to prevent movement 70 of the guides away from the brace-bars, and means for holding the extensible brace-bar at times against extension.

3. An instrument of the class described comprising a foldable frame including upper 75 and lower spaced guides, slides removably mounted in the guides, a marker connected with one of the slides, a brace-bar pivotally connected with the end of each guide, an extensible brace-bar pivotally connected at its 80 ends with the other ends of the guides, said brace-bars and guides having mutually-engaging fingers disposed to prevent movement of the guides away from the brace-bars, means for holding the extensible brace-bar 85 at times against extension, and supporting-legs connected with the frame at the unions of the guides and brace-bars, one of said legs having a notch therein arranged to receive one of the guides when the frame is in folded 90 position.

4. In an instrument of the class described, the combination with upper and lower spaced guides, said lower guide comprising a plate having a longitudinal slot therein, of a slide 95 carried by the upper guide for movement longitudinally thereof and for rotation with respect thereto, an arm slidably engaged with said slide for movement horizontally, means for holding the arm at different points of 100 its movement, said arm having a downwardly and rearwardly turned end located above the lower guide, a plate disposed beneath the lower guide, a pin carried by the 105 plate and loosely engaged in the slot of the lower guide and rigidly engaged in the rearwardly-turned end of the arm, said end of the arm and plate extending laterally beyond the slot of the lower guide, a horizontal arm 110 slidably connected with the plate beneath the lower guide, a depending marker carried by the last-named arm, and means for holding said arm at different points of its sliding movement.

In testimony whereof we affix our signatures in presence of two witnesses.

CHESTER HANES.
ROBERT H. MONTEITH.
